UNITED STATES PATENT OFFICE.

GEORGE L. HARVEY, OF CHICAGO, ILLINOIS.

CIGARETTE-DISPENSING BOX.

1,096,910.

Specification of Letters Patent.

Patented May 19, 1914.

Application filed December 10, 1913. Serial No. 805,698.

To all whom it may concern:

Be it known that I, GEORGE L. HARVEY, a citizen of the United States, residing at Chicago, in the county of Cook and State 5 of Illinois, have invented certain new and useful Improvements in Cigarette-Dispensing Boxes, of which the following is a specification.

My invention has for one of its objects 10 the provision of an original package of attractive appearance for cigarettes, and of such shape and form as to eliminate objectionable sharp edges and corners, thereby affording a package which apparently occupies less space than the usual cigarette 15 boxes of rectangular form and also because of its form preserving the shape of the garment pocket in which it is carried.

A further feature of the invention is the 20 provision of such a package or container which may be readily opened and when open, constituting a carrying-case of convenient form enabling the cigarettes to be withdrawn singly and with facility.

25 These and other objects are attained by forming the original cigarette package of a substantial elliptical shape with a readily detachable cover at one corner whereby when the cover is removed the box serves as a pocket dispensing case the cigarettes 30 presenting themselves singly at the corner opening in position to be grasped by the fingers and removed.

In order that the invention may be readily 35 understood a cigarette box embodying the same is set forth by way of illustration in the accompanying drawing and in the detailed description based thereon.

In the drawing Figure 1 represents in 40 perspective such a cigarette box as it comes from the dealer; Fig. 2 is a detail view of the cover removed; Fig. 3 is a view similar to Figs. 1 and 2 showing the box as a pocket case with a cigarette in position to be with- 45 drawn; and Fig. 4 is a fragmentary view in transverse section taken on the line below the top of the box.

The reference numeral 11 designates the 50 box body to which is permanently secured a bottom having a marginal band 12 over-lapping the lower edge of the box body and serving as an ornamental finish. A top 13 is likewise permanently secured to the box and provided with a marginal finishing 55 band 14. The material of the box body 11, the top 13 and the band 14 are severed along

an oblique line 15 so as to provide a removable cover 16 at the corner of the box. The line of juncture 15 is bridged by the outer covering material 17 of the box which is 60 ordinarily of paper and along the line of juncture beneath the paper is arranged a cord 18 having a projecting end and adapted when pulled to sever the paper and thus detach the cover 16 as will be readily understood. 65

The cover having been removed the box assumes the form shown in Fig. 3 constituting a convenient pocket case which, by reason of its flattened elliptical shape, may be 70 readily carried within the vest pocket without distorting the set of the garment to any appreciable extent. The interior dimensions of the box at its two edges is preferably such as to accommodate a single cigarette while 75 in the wider portion of the case intermediate the edges the cigarettes may lie side by side in compact relation. From Fig. 3 it will be observed that the corner cover includes only so much of the top 13 as over- 80 lies one cigarette at the edge of the box and that when the cover is removed the cigarette 19, which occupies the position at the edge of the box, is exposed in a position to be grasped by the fingers and removed while 85 the other cigarettes are prevented from passing through the opening. Moreover, the dimensions of the box are such that the cigarette at the opening is frictionally held between the edge walls so as to prevent it ac- 90 cidentally leaving the box. Obviously when one cigarette is removed from the edge of the box another will, when the box is tilted, drop into position at the opening. The shape of the box is, moreover, conducive to 95 economy in manufacture, as the body thereof may be formed upon a mandrel in lengths of tubular or elliptical cross-section and thereafter cut into sections of the requisite length, and the bottoms and tops then at- 100 tached expeditiously by hand or by machines of simple construction.

I claim:

1. An original package for cigarettes or the like comprising a box of substantially 105 elliptical cross section, the interior dimensions of the box at its two edges being such as to accommodate a single cigarette, and a cover for one corner of the box detachably connected thereto along an oblique line, and 110 means to facilitate the removal of the cover, the detachable cover including so much of

the top and edge of the box as overlies the end of a single cigarette, substantially as described.

2. An original package for cigarettes and
5 the like of elongated elliptical cross-section,
the interior dimensions of the edge portion
being such as to accommodate one only of
the cigarettes or other contained articles,
said package having a detachable section
10 comprising a part of the side and end of the
package and located at the edge portion of
the package and permitting after its detach-

ment the grasping and endwise withdrawal
of a single exposed cigarette or other article
through the opening provided by the re- 15
moval of said section.

In testimony whereof I have hereunto
signed my name in the presence of two sub-
scribing witnesses.

GEORGE L. HARVEY.
